UNITED STATES PATENT OFFICE

2,130,051

SWEDGER

Frank A. Ward, Hollister, Calif.

Application May 18, 1937, Serial No. 143,395

1 Claim. (Cl. 76—4)

My invention relates generally to swedging apparatus, and particularly to a crown swedger adapted to make grooves in the die to facilitate splitting of the die into halves, and to hold the split die in position with the gold shell therein while the plunger of the apparatus is forcing material into the shell to expand the same into the cavity of the die formed by the plaster tooth.

Other important objects of my invention will be apparent from a reading of the following description taken in connection with the drawing, wherein for purposes of illustration I have shown a preferred embodiment of my invention.

In the drawing:—

Figure 1 is a general transverse vertical sectional view taken through an embodiment of the invention and showing a design in place in the swedging cup.

Figure 2 is a top plan view of the swedging cup showing the grooved forming ribs therein.

Figure 3 is a bottom plan view of Figure 2.

Figure 4 is a transverse vertical sectional view taken through the swedging cup.

Referring in detail to the drawing, the numeral 5 generally designates a suitable base or bed which is formed with a vertical cylindrical recess 6 opening through its top and receiving the conformably-shaped swedging cup 7. The recess 6 has at its upper end a laterally extended portion 8 to receive the lower end of the plunger barrel 9 which fits snugly around the exposed upper part of the swedging cup 7 as indicated in Figure 1 of the drawing.

The plunger barrel 9 extends above the base 5 and telescoped therein is the plunger 10 which has a suitably formed head at its upper end and a plain or other suitable formation containing bottom 12' for forcing material into the die which is represented by the numeral 13. The structure described in general terms above is considered no part of the present invention as such, but the essence of the invention is considered to reside in the formation of the swedging cup 7.

The swedging cup 7 is in accordance with the present invention provided with the tapering

opening 12 which opens through the bottom of the cup as indicated by the numeral 13', the opposite sides of the wall of the opening 12 being formed with triangular cross section ribs 14 and 15 or ribs of other cross sections which extend in a radially inward direction and in a vertical direction and in general conform in slant to the slant of the walls of the opening 12 and terminate flush with the bottom of the cup 7 while extending to the top of the opening 12.

In certain work it is a distinct advantage to be able to accurately and easily split the die formed in the opening 12 of the cup 7, and the present invention, through the provision of the ribs 14 and 15 forms in the opposite sides of the die 13 accurately opposed and formed grooves. These grooves produce weakened lines in the opposite sides of the die which facilitate accurately splitting the die with a minimum amount of work. Apparatus of this character is especially useful in practicing dental manufacture.

Although I have shown and described herein a preferred embodiment of my invention, it is to be definitely understood that I do not desire to limit the application of the invention thereto, and any change or changes may be made in the materials and in the structure and arrangement of the parts, within the spirit of the invention and the scope of the subjoined claim.

What is claimed is:—

A wedging device of the class described comprising a base having a circular opening therein, a circular swedging cup located in the opening and said base having an annular groove in its upper portion surrounding the upper portion of the cup, a barrel having its lower end fitting in the groove, with the upper portion of the cup fitting in the lower end of the barrel, a plunger in the barrel, said cup having a downwardly tapering opening passing therethrough with the small end of the opening opening out through the bottom of the cup and a pair of ribs formed on the walls of the opening and arranged diametrically opposite each other.
